UNITED STATES PATENT OFFICE.

RICHARD F. SCHIELE, OF GLEN ELLYN, ILLINOIS.

COMBINED SPOTLIGHT AND CIGAR LIGHTER.

Application filed May 17, 1893. Serial No. 639,660.

My invention relates to an improvement in a combined spot light and cigar lighter and has among its objects the production of a device of the kind described, which is 5 simple, convenient, compact, durable, reliable, efficient and satisfactory for use wherever found applicable.

Another object of my invention is to provide means for universally mounting such 10 a device upon a wind-shield or other supporting panel so that it may be operated as desired.

Another object of my invention is to provide switch means, whereby said light and 15 lighter may be operated in unison or successively as desired.

Many other objects and advantages of the 20 construction herein shown and described will be obvious to those skilled in the art from the disclosures herein given.

To this end my invention consists in the novel construction, arrangement and combination of parts herein shown and described, and more particularly pointed out in the 25 claims.

In the drawings, wherein like reference characters indicate like or corresponding parts:

Fig. 1 is a vertical section through my 30 device;

Fig. 2 is a section taken substantially on line 2—2 of Fig. 1;

Fig. 3 is a section taken substantially on line 3—3 of Fig. 1;

Fig. 4 is a detail showing the universal 35 joint portions disassembled;

Fig. 5 is a section taken substantially on line 5—5 of Fig. 1;

Fig. 6 is a section taken substantially on 40 line 6—6 of Fig. 1;

Fig. 7 is a fragmentary section showing 45 modified form of device;

Figs. 8 and 9 are sections showing modified forms of switch contact arrangements;

Fig. 10 is a fragmentary section showing 50 a modified form of device;

Fig. 11 is a section taken substantially on line 11—11 of Fig. 10;

Fig. 12 is a section taken substantially on 55 line 12—12 of Fig. 10;

Fig. 13 is a section showing a modified form of switch mounting, and

Fig. 14 is a diametric view of the wiring 60 of the device shown in Figs. 1 and 7.

In the drawings, 1 indicates a spot light of

any desired size and shape and preferably having a rearwardly extending tubular extension 2. A casing 3, preferably hollow or tubular, as shown, is provided with a bore 4 therethrough to receive the rear end of the extension part 2 of the spot light 1 and is connected thereto by means of a set screw 5 or in any other suitable or equivalent manner. A cigar lighter 6 of any suitable or preferred form, and in the modification shown, of the resistance type which becomes sufficiently heated so as to become ignited whereby the same may be applied to the end of a cigar to light the same is removably arranged in the bore of said casing. Insulation 7 may be arranged between the part 6 and the casing 3, whereby the lighter element may be grasped to remove the same for use from the casing.

As is shown, the lighter is preferably 75 frictionally arranged in the casing so as to be easily removable therefrom. A sheath or sleeve 8, preferably of a rigid material is carried by the lighter so as to project therefrom and is insertable into the casing and 80 through the part 2 for quite a substantial distance.

A switch, comprising a relatively stationary part 9 and a movable part 10 is insertable into the bore 4 of the casing and carries 85 suitable lead wires leading to the light and lighter, respectively, the switch part 9 having terminal contacts 11, 12 and 13 projecting therefrom. It will be noted that the lead wire from the switch part 9 to the cigar 90 lighter, and which in the form shown is designated 12' is not arranged across the shortest distance between the switch and cigar lighter, but extends through the sleeve 8, as shown, thus enabling the lighter to be 95 removed a substantial distance from the casing while using and doing away with the necessity of providing a spring reel or other means for keeping the lead wire 12' from becoming tangled.

The movable switch member 10 is preferably rotatable in the bore of the casing and is held in place against accidental movement in any desired manner. The inner portion of the movable switch part is preferably of metal, as at 14, and has a portion of its surface opposite the contacts 11, 12 and 13 recessed or cut back as at 14' so that when the knob of the movable switch part is manually rotated, the portion 14' will not contact 110

with any of the switch terminals to provide an electric connection therebetween. It is apparent that when the terminals 11, 12 and 13 are arranged approximately 60 degrees apart, as shown in Figs. 5 and 14, the spot light and lighter will be operated successively as the switch knob is rotated. The wires may be held to the casing in any desired manner, as for instance, by clamps 15, 10 as shown in Fig. 1, and I prefer to provide an armor for the wires so that the armor may be soldered at the clamps and a good ground connection may be made between the casing and the wires. In the form shown, 15 the casing is a common ground for both the lamp and lighter. It is obvious that the grounding could be done in various other ways, as desired.

In order to mount the device upon the 20 windshield or panel and permit a universal movement of the same therein, I have provided a special type of mounting. The mounting comprises three main parts, consisting of a central block 16, and end blocks 25 19, the central block having its two opposite side faces plane and parallel and its peripheral surface intermediate the plane surfaces made spherical. A pair of trunnions 17 are arranged to project in diametric alignment from the plane surfaces of the block. A bore 18 is formed through the central portion of the block, as shown, for the reception of the extension part 2, said bore having its 30 axis arranged perpendicular to the axis of the trunnions 17.

A pair of end members 19 are provided to cooperate with the central block member 16, these end block members each having a plane surface and a spherical peripheral surface 40 terminating at the plane surface, as shown. Bores 20 are arranged centrally of the members 19 through the plane surfaces to rotatably receive the trunnions 17 of the central block member, the ends of the trunnions being peened over as at 21 after the block members have been assembled to hold the universal joint assembled. An arcuate slot or groove 22 is provided in the spherical peripheral portion of the end block members. 45

The wind-shield or other panel upon which the device is to be mounted is provided with an opening therethrough sufficiently large to receive the universal joint, and clamping rings 24 and 25 are arranged on the opposite sides of the wind-shield surfaces and are connected together by any suitable means, as at 55 26. The inner surfaces of the rings 24 and 25 are made concave so as to receive the convex surface of the universal joint, and the ring 24 has lugs 27 projecting radially inwardly therefrom to slide in the grooves 22 of the universal joint.

It is apparent that the universal movement 60 of the device is permitted in a pair of mutually transverse planes, one axis of rotation

being about the axis of the trunnions 17 and the other or horizontal axis of rotation being in the plane of the grooves 22.

In the form shown in Fig. 7, the lighter member 6 is preferably arranged so as not 70 to be removable from the casing. In other respects, the device is substantially similar to that previously described. In Figs. 8 and 9, the contact points 11, 12" and 13" are arranged in close proximity to each other so 75 that the switch part 10 may be adjusted so that the spot light may be lit while the cigar lighter is energized.

In the modification shown in Figs. 10-12, inclusive, the contact 10' carried by the 80 switch member 10 is of the spring ring type, as shown more clearly in Fig. 12, the knob 10 being rotated to throw the light on or off, as desired. There is a separate switch 85 provided for the cigar lighter, said switch being shown at 30 and adapted to be pressed inwardly whenever the lighter is to be energized.

In case it is desired to mount the switch upon the panel-board instead of on the casing 3, a separate sleeve or casing part 31 is provided as shown in Fig. 13, said sleeve being adapted to receive the switch parts and be secured to the panel-board by screws or the like through the apertures 32. 95

In Fig. 14 is shown a diametric representation of the wiring circuit used in connection with the forms of device shown in Figs. 1 and 7. The switch terminals 11, 12 and 13 are arranged approximately 60 degrees 100 apart, as shown, there being a wire leading from one of the terminals to the lighter, another wire leading from the terminal to the lamp, and another wire leading from the other terminal to the battery. The 105 lamp, the lighter and the battery all have a common ground, and when the knob portion 10 of the switch is rotated either the lamp or the lighter will be energized.

In the position shown in Fig. 14, both the 110 lighter and the lamp are unenergized because the switch is not connected in the circuit of the battery.

The device may be used as a trouble light by removing the clamping means 24 and 25, 115 the joint being held together and prevented from falling apart by the peened over trunnions 17.

Having thus described my invention, it is obvious that various immaterial modifications may be made in the same without departing from the spirit of my invention; hence I do not wish to be understood as limiting myself to the exact form, construction, arrangement and combination of parts 125 herein shown and described or uses mentioned.

What I claim as new and desire to secure by Letters Patent is:

1. In combination, a lamp, a lighter re- 130

movably secured thereto, an electrical contact for each of said members, and a movable contact carried by said lighter and operable to selectively engage said contacts.

5 2. In combination, a lamp, a lighter, said members having a bayonet joint therebetween so that they may be detachably secured together, an electrical contact carried by said members, a movable contact carried 10 by said lighter and selectively engageable with either of said contacts, and manually operable means for separating said movable contact and the lamp contact.

3. In a device of the kind described and 15 in combination, a tubular casing, a rotatable switch insertable thereinto, a cigar lighter removably insertable in said casing, a spot light having an extension insertable into said casing so as to be carried thereby, a 20 universal joint arranged intermediate said light and lighter, and means for controlling said switch to energize said light or lighter irrespective of whether said lighter is in or out of the casing.

25 4. In a device of the kind described and in combination, a tubular casing, a cigar lighter removably insertable therein, a spot light having an extension insertable into said casing so as to be carried thereby, a

switch carried by said casing and controlling 30 the light and lighter at will, and a lead wire extending from said lighter to said switch and projecting into said casing for a substantial distance beyond said lighter and said switch so that said lighter may be temporarily removed from said casing while energized and electrically connected thereto.

5. In a device of the kind described and in combination, a tubular casing, a cigar lighter and a spot light carried thereby, a 40 rigid sleeve carried by said lighter and projecting into said casing a substantial distance, and a switch operable to control said lighter and light and including a lead wire leading from said lighter through said sleeve 45 and connected to said switch.

6. In a device of the kind described and in combination, an electric spot light, an electric cigar lighter, a switch, a common carrying means for said light, lighter, and 50 switch, and means for universally mounting said last-mentioned means to a panel so that the light is arranged on one side of the panel and the lighter and switch on the other side.

In testimony whereof, I have hereunto signed my name.

RICHARD F. SCHIELE.
